UNITED STATES PATENT OFFICE.

DANIEL ABREY, OF PHILADELPHIA, PENNSYLVANIA.

HOISTING MECHANISM.

No. 818,212.

Specification of Letters Patent.

Patented April 17, 1906.

Application filed August 10, 1905. Serial No. 273,697.

To all whom it may concern:

Be it known that I, DANIEL ABREY, a citizen of the United States, residing at Philadelphia, in the county of Philadelphia, in the 5 State of Pennsylvania, have invented a new and useful Improvement in Hoisting Mechanism, of which the following is a specification.

Figure 1 is an elevation of mechanism embodying my improvements, part of the frame being broken away. Fig. 2 is a similar view showing my improvements embodied in another form. Fig. 3 is a similar view showing still another form of apparatus in which my 15 invention may be embodied. Fig. 4 is an end view of the device shown in Fig. 1. Fig. 5 is an end view of the device shown in Fig. 2, and Fig. 6 is an end view of the device shown in Fig. 3.

My improvement in hoisting-machines is more particularly intended for passenger and freight elevators, but equally applicable for other kinds of hoisting.

The improvement relates to a better method of propelling hoisting-machines by a new way of using worm-gearing and is described as follows:

Figs. 1, 2, and 3 are front elevations of three hoisting-machines and each machine 30 driven by two worm gear-wheels, (marked on the illustrations C and C², &c.) Said worm-wheels of each machine are driven by two parallel shafts F and F² by right and left hand worms firmly mounted on each shaft 35 and the worms meshing into the worm-wheels C and C², &c., on opposite sides. The parallel shafts F and F² are driven by the spur-gears K and K², which are firmly mounted on said shafts and mesh with each other, said 40 gear-wheel K² being driven by the pinion J in mesh therewith and which is firmly mounted on the driving-shaft L. It will thus be seen that through the operation of the pinion J the gears K² and K are caused to revolve in 45 opposite directions, thereby operating the parallel shafts in such directions, respectively.

Fig. 1 has the two worm-wheels C and C² firmly mounted on the shafts of the two 50 drums B and B², and whenever the worm-wheels revolve the hoisting-drums are working.

Fig. 2 has one worm-wheel C firmly mounted on the shaft of the drum B and the other 55 worm-wheel C' firmly mounted on the transverse shaft, on which is also firmly mounted

the spur gear-wheel M, which meshes into the similar spur gear-wheel M², firmly mounted on the shaft of the other drum B'. Therefore when the worm-wheels C and C' are 60 driven the machine is working.

Fig. 3 has one worm-wheel C firmly mounted on the shaft of the drum B and the other worm-wheel C³ firmly mounted on a transverse shaft, on which is also firmly mounted 65 the spur gear-wheel M³, which meshes into the similar spur gear-wheel M, firmly mounted on the shaft of the drum B. Therefore when the worm-wheels C and C³ are driven the machine is working.

The hoisting-machine (marked Fig. 1) has two winding or hoisting drums B and B² for pulling or slackening the rope or chain D, and one end of it is fastened to the drum B, and the other end of it is fastened to the drum 75 B². When the machine is in motion, each drum pulls and winds on the rope or unwinds and slackens it.

The hoisting-machine (marked Fig. 2) has two drums, each revolving in the same direction, but alternately forward and backward. The rope or chain is wound several times around the hoisting-drums B and B' to give the drums sufficient hold of the rope to prevent its slipping, and when one end of the 85 rope is hoisting a load the other end of the rope will be unwinding from the drums; but, alternately, either end of the rope can be used alike to lift a load.

The hoisting-machine (illustrated in Fig. 3) 90 has only one winding or hoisting drum B. One end of the rope or chain D is fastened to the drum, and the other end is fastened to the load to be moved.

The belt-pulleys (shown in Figs. 1, 2, and 3 95 in the drawings mounted on the driving-shaft L and marked H, H², and H³) is a common contrivance of two loose pulleys and the center pulley fast to the driving-shaft, by which cross and straight belts are used to 100 drive the hoisting-drums forward and backward or stop the machine, as may be required.

It will be understood, of course, that any 105 of the well-known methods and apparatus for imparting motion to the power-shaft may be employed in using my device.

The crank-wheel (marked N in the drawings and shown in Fig. 3) is firmly mounted on the driving-shaft L and is intended to operate the machine as may be required.

Having thus fully described my invention,

what I claim as new, and desire to secure by Letters Patent of the United States, is—

1. In a hoisting-machine gearing comprising a plurality of worms in pairs, transverse shafts, worm - wheels thereon the opposite sides of which engage said worms of the respective pairs and drums, each actuated from one of said worm-wheels.
2. In a hoisting-machine gearing comprising a plurality of worms in pairs, transverse shafts, drums carried thereby, and worm-wheels mounted on said shafts and meshing at opposite sides with the worms of a pair.
3. In a hoisting-machine, a power-shaft, a gear carried thereby, parallel shafts, a gear on each shaft in mesh with each other and one of said gears in mesh with the gear of the power-shaft, a right and left hand worm mounted on each of said parallel shafts, transverse shafts

journaled between and at right angles to the 20 worm - shafts and actuated thereby, and a drum mounted on each of said transverse shafts.

4. In a hoisting-machine, parallel shafts, a right and left hand worm mounted on each of 25 said parallel shafts, transverse shafts journaled between and at right angles to the worm - shafts and actuated thereby, a drum mounted on one of said transverse shafts and means for imparting motion to said parallel 30 shafts.

In testimony whereof I have signed my name to this specification in the presence of two subscribing witnesses.

DANIEL ABREY.
